UNITED STATES PATENT OFFICE.

CHARLES LEA, OF DORCHESTER, MASSACHUSETTS, ASSIGNOR TO AMERICAN WARP DRAWING MACHINE COMPANY, A CORPORATION OF MAINE.

MACHINE FOR PERFORATING PATTERN-SHEETS.

1,196,707.

Specification of Letters Patent. Patented Aug. 29, 1916.

Application filed April 22, 1912. Serial No. 692,470.

To all whom it may concern:

Be it known that I, CHARLES LEA, a citizen of the United States, and a resident of Dorchester, county of Suffolk, and Commonwealth of Massachusetts, have invented an Improvement in Machines for Perforating Pattern-Sheets, of which the following description, in connection with the accompanying drawings, is a specification, like characters on the drawings representing like parts.

My invention relates to perforating machines and more particularly, though not exclusively to machines for perforating pattern sheets for warp drawing machines, and will be best understood by reference to the following specification, when taken in connection with the accompanying illustration of one specific embodiment thereof, while its scope will be more particularly pointed out in the appended claims.

In the drawings:—Figure 1 is a longitudinal vertical sectional view, partly in elevation, of a perforating machine embodying my invention; Fig. 2 is an elevation, partly in vertical section, of the machine as viewed from the left-hand side of Fig. 1; Fig. 3 is a detail sectional view on the irregular line 3—3 of Fig. 2 looking toward the left, showing a portion of the paper-feeding and drum-rotating mechanism; Fig. 4 is a detail plan view of a portion of the table with the sheet guides and sheet tensioning device. Fig. 5 is a detail plan of a portion of the machine, showing the punch-actuating drum and its inclosing casing or guard; Fig. 6 is a detail sectional view on line 6—6 of Fig. 2 looking toward the right, showing the brake; Fig. 7 is a detail sectional view on line 7—7 of Fig. 2; Fig. 8 is a sectional view on line 8—8 of Fig. 7; Fig. 9 is a plan of a portion of an illustrative pattern sheet perforated on the machine; and Fig. 10 is a plan of a portion of a designer's draft corresponding to the portion of the pattern sheet illustrated in Fig. 9.

Referring to the drawings, and to the embodiment of my invention which I have there disclosed for illustrative purposes, I have there shown a perforating machine having a frame 11 for supporting the operative parts of the machine. On this frame, there may be mounted suitable means for supporting a supply of the sheet material,

herein a shaft 12 supported on the bracket 55 or brackets 13 and having flanges 14, between which may be placed a roll 15 of sheet material 16, which may be thin sheet metal, paper, or any other suitable material.

The sheet material may be led from the 60 roll across a suitable table or platen 17, and may be guided on the latter by guides 18 and 19 engaging the edges of the material. Preferably these guides are mounted in grooves 20 and 21 respectively, provided in 65 the table 17. There may be provided grooves 22 and 23, also adapted to receive the guides 18 and 19 respectively. At certain times in the operation of the machine, it may be desirable to shift the guide 18 70 from the groove 20 to the groove 22, and the guide 19 from the groove 21 to the groove 23, to shift the sheet transversely for a purpose which will appear hereinafter. For narrower strips of the sheet material, 75 there may be provided grooves 24, 25, 26 and 27, adapted to receive the guide 19.

There may be provided suitable sheet tensioning means, herein a friction bar 28 resting upon the sheet material and pressed 80 against the latter by suitable means, herein a pair of springs 29, encircling two studs 30 respectively, passing loosely through the bar 28, and secured to the frame 11.

It will be observed by reference to Fig. 1 85 that the guides 18 and 19 are provided with shallow notches terminating at their ends adjacent opposite edges of the friction bar 28, and that the friction surface of the latter is intermediate the top and bottom of 90 the guides. It follows that the latter cannot become displaced without first removing the friction bar.

The sheet material may be fed across the 95 table 17 by suitable feeding means, preferably one which will impart a positive feeding movement to the sheet and preferably impart to the latter a step-by-step feeding movement, with its feeding movement in the intervals between the punching operations, 100 as will appear hereinafter. Preferably the sheet-feeding mechanism comprises a feed-wheel, or a pair of feed-wheels, 31 provided with suitable means, herein teeth 32, for engaging rows of perforations 33 located adjacent opposite edges respectively of the sheet. These perforations may be provided in the sheet prior to the placing of the latter 105

upon the machine, but preferably they are punched simultaneously with the punching of other perforations in the sheet, as will appear hereafter.

- 5 The feed-wheels 31 may be mounted on a shaft 34 journaled in suitable bearings 35 and 36 and may be given an intermittent rotative movement by any suitable mechanism. Herein for this purpose, I provide a ratchet 10 37 secured to the shaft 34, and coöperating with a suitable pawl 38 carried by a pawl-carrier 39, mounted to slide vertically on the frame 11, herein being provided with slots 15 40 and 41, the former receiving a stud 42, and the latter receiving a shaft 43. The pawl 38 may be mounted to slide in a recess 44 provided in the pawl-carrier 39, and may be held in yielding engagement with the ratchet 37 by a suitable spring 45 located in 20 said recess and bearing against the inner end of said pawl. The pawl-carrier 39 may be given a vertical reciprocatory motion by suitable means, herein an eccentric 46, engaging a horizontal slot 47 provided in said 25 pawl-carrier. This eccentric may receive a rotary motion from a shaft 48, to which it is secured, said shaft also being driven in any suitable manner, as for example by being provided with a small fly-wheel 49, having 30 a grasping handle 50. By this means, the pawl 38 is given a vertical reciprocatory motion, and consequently engages successive teeth on the periphery of the ratchet 37, thus imparting an intermittent rotary motion to 35 the latter. There may be provided a stop-pawl 51, pivotally mounted on a stud 52, and engaging the ratchet 37 to prevent reverse rotation of the latter. If desired, this stud may be made horizontally adjustable in a 40 slot 53 provided in the frame 11, and may be provided with a nut 54 to hold the same in the desired position of adjustment.
- The feed-wheels 31 may be adjusted longitudinally of their axes, and relatively positioned with respect to the perforating means in a plurality of predetermined positions transversely of the sheet, by providing the shaft 34 with a sleeve 55 having grooves 56 and 57, either of which is adapted to 45 receive a positioning pin 58. Herein this pin is arranged tangentially with respect to the sleeve 55 and is mounted to slide longitudinally in a suitable guide-way 59 provided in the bearing 35. This pin serves 50 normally to lock the sleeve 55, and consequently the shaft 34 and feed-wheels 31, against longitudinal movement, since the sleeve is mounted on a reduced portion 60 of the shaft between a shoulder 61 and a 55 washer 62 secured to the outer end of the sleeve. The pin may be provided with a reduced portion 63, which when the pin is moved from the position shown in Fig. 8 toward the left into register with the periphery of the sleeve 55, will permit the latter

to be moved together with the shaft 34 and feed-wheels 31 longitudinally a distance equal to the distance between the two grooves 56 and 57. The sleeve 55, shaft 34 and feed-wheels 31, may then be locked in their new 70 position by sliding the positioning pin longitudinally into the proper position to engage with the groove 57. The longitudinal movement of the positioning pin 58 may be limited by suitable means, herein screws 64 75 and 65 threaded into opposite ends thereof, and having heads larger in diameter than the body portion of the pin.

The sheet may be perforated by any suitable perforating mechanism, but I prefer to 80 employ for this purpose a series of punches 66 of any desired number, herein eight, arranged in a row extending transversely of the sheet, and I may also provide two punches 67 located at opposite ends respectively of said row. Herein the punches 67 are utilized for the purpose of punching the two rows of perforations 33 adjacent opposite edges respectively of the sheet to receive the teeth 32 of the feed-wheels 31, 90 while the remaining punches 66 are utilized for punching rows of suitable perforations for the pattern located between the two rows of perforations 33. All of the punches 66 and 67 are identical in construction, except that preferably the working ends of the punches 66 are all suitably shaped to punch elongated perforations in the sheet, while the punches 67 are preferably formed to punch the perforations 33 square. In other 100 respects, the punches may be identically similar in construction, and a detailed description of one will suffice for all.

Each punch 66 is preferably generally cylindrical in form, being guided in holes 68 provided in a transverse guide-bar 69, and each punch is provided with a rectangular shank 70, working in a correspondingly shaped hole 71 provided in a guide-plate 72. This guide-plate is suitably placed above the upper surface of the table 17 to permit the passage of the sheet therebetween. The punches 66 coöperate with a suitable die-plate 73 having holes 74 corresponding in shape to the shanks 70 to receive the latter. This die-plate may be set into a suitable recess 75 provided in the table 17, and the latter may be provided with a transverse slot 76 having sufficient clearance to allow the free escape of the material punched by the punches. If desired, the guide-bar 69 and guide-plate 72 may be provided with a beveled recess 77, permitting inspection of each transverse set of perforations as the latter appear to the view of 120 the operator just after being punched when the sheet has been fed one feed-step.

The punches 66 and 67 may be actuated by any suitable means, herein wipers 78 for the punches 66 and similar wipers 79 for 125

the punches 67 mounted on a transverse pivot 80 and engaging said punches respectively, the latter being for this purpose preferably provided with screws 81 and 82 respectively, threaded into the upper ends thereof. The heads of these screws also serve as abutments for springs 83 and 84 respectively, encircling the punches 66 and 67, and bearing at their lower ends against the guide-bar 69.

The two wipers 79 receive their movement from suitable means, herein two series of pins 85 carried by a drum 86, the latter being provided for this purpose with two series of holes 87 to loosely receive these pins. The wipers 78 may be similarly actuated by pins 88, also carried by the drum 86, the latter for this purpose being provided with a plurality of series of holes 89 loosely receiving said pins. The two series of pins 85 will always remain in their places in the drum 86, so that at all times in the operation of the machine the two punches 67 will serve to punch the two rows of perforations 33 adjacent the opposite edges of the sheet to provide for the feeding of the latter. The various pins 88, however, will be removed from their respective holes in the drum 86 from time to time, and will be variously arranged according to the requirements of the pattern which is to be perforated in the pattern sheet. For this purpose, the pins 88 as before stated are loosely held in the drum 86, so as to be capable of ready removal and re-arrangement at the will of the operator. It must be evident, therefore, that provision must be made for the convenient insertion and removal of the pins, and their retention in the drum during the rotation of the latter. For this purpose, I preferably provide the drum 86 with a cylindrical casing 90 inclosing the drum and having in its upper side an aperture 91 permitting the removal and replacement of the pins when the latter are at the upper side of the drum. The internal diameter of this casing, however, is such that it engages the outer ends of the pins and holds the latter in place after the pins have passed beyond the aperture 91. The casing 90 is provided on its under side with an aperture 91^x, to permit coöperation of the wipers with the pins. The casing 90 is mounted upon and secured against rotation by two uprights 92 and 93 forming a part of the frame 11.

The drum 86 receives its rotative movement in any suitable manner, as by being secured to the shaft 43 hereinbefore referred to, the latter being journaled in the uprights 92 and 93 just described. This shaft may have secured thereto a ratchet 94, coöoperating with a pawl 95 pivoted on the pawl-carrier 39 hereinbefore described, and held in operative engagement with said ratchet by a suitable spring 96. When the pawl-carrier 39 is reciprocated as hereinbefore described the pawl 95 acts through the ratchet 94 and shaft 43 to impart an intermittent rotative movement to the drum 86. It will be observed that the pawl 38 hereinbefore described operates on the up-stroke of the pawl-carrier 39, while the pawl 95 operates on the down-stroke of the pawl-carrier, and hence the feed-wheels 31 and the drum 86 are rotated alternately, the consequence being that the sheet will be held stationary while being punched, and will be fed forward a predetermined distance between each of the punching operations. As the drum 86 may have a tendency to over-travel, or in other words to continue to rotate after the feed-pawl 95 has started on its return movement, the drum may be provided with suitable means, herein a brake 97 surrounding the shaft 43, tending to resist turning movement of the latter. This brake may be held against rotation by a stud 98, and may be provided with a split portion 99 and a screw 100, by means of which the brake may be contracted to increase its braking effect upon the shaft. If desired, the shaft 43 may be provided with a small hand-wheel 101, by means of which the drum 86 may be manually rotated independently of the operation of its driving mechanism hereinbefore described.

By the perforating mechanism hereinbefore described, the sheet may be punched according to any selected pattern and fed in a step-by-step movement as it is punched, the punching operations alternating with the intermittent feeding movements of the sheet. In some cases, it may be desirable to provide a guide 102 placed above the sheet to hold the latter in feeding engagement with the teeth 32 of the feed-wheels 31. This guide may be adjustably secured to the front piece of the guide-bar 69 by screws 103 passing through vertical slots 104 provided in the guide 102. The sheet material as it is fed from a roll naturally tends to curl somewhat, and this tendency, especially with the tendency of the punches to exert an upward pull on the material when withdrawing therefrom, would naturally result in the sheet becoming disengaged from the feed-wheels at times. Such disengagement, however, is effectually prevented by the guide 102, which insures a positive feeding engagement of the sheet with the feed-wheels.

In order to assist the operator in placing the pins in the drum according to the desired pattern, I preferably employ an index plate 105, bearing suitable characters placed opposite corresponding circumferential rows of holes in the drum and corresponding to similar characters on the designer's draft of the pattern, the latter being shown in Fig. 10. Herein the character at one end of the

index plate is "R," meaning "Reed," and the character at the other end is "W," meaning "Warp," while the intervening characters are the numerals 1 to 6 inclusive. By 5 the use of this index, the operator is enabled to place a longitudinal series of pins in the drum in accordance with dots or other symbols upon the designer's draft or chart, indicating the positions for the placing of 10 the pins.

It will be convenient to provide some 15 means to enable the operator to determine when a certain longitudinal row of pins placed in the drum, subsequently arrives after 180 degrees of rotation of the latter in 20 position to punch that particular sequence of perforations in the sheet. To that end, therefore, I preferably employ two indicator disks 106 and 107 secured to the shaft 43, at 25 opposite ends respectively of the drum 86. These disks may be provided with suitable characters, herein a series of numerals 1 to 12 inclusive on their peripheries, corresponding to the twelve longitudinal rows of 30 holes in the drum. The numerals of one disk, however, will be placed six numbers apart from the numerals of the other, or in other words, the numeral "1" on one disk will be placed opposite the numeral 7 on the other disk, and the remaining numerals will be correspondingly placed.

Suitable means may be provided for enabling the operator to determine from the numerals on the disks the location of a certain longitudinal series of pins in the drum. For this purpose, I preferably provide the casing 90 with a notch or aperture 108, through which the numerals of the disk 106 may be viewed one by one, as they pass said 40 notch or aperture in rotation, and I provide a similar notch or aperture 109, through which the numerals of the disk 107 may be viewed as they pass in rotation. I preferably associate with the notch 108 the word 45 "Set," and with the notch 109 the word "Punch." These words may be placed adjacent their respective notches in any suitable manner, as by being stamped on the casing 90. It will be observed that the notches just 50 described are located a short distance at one side of a vertical plane containing the axis of the drum and therefore somewhat out of register with the numerals on the disks. Hence just before a given set of punches is 55 actuated by the drum to perforate the paper, the numeral designating that particular set of pins controlling said punches will appear in the notch or aperture 109 at the word "Punch." It will now be evident that if 60 the operator, referring to the word "Set" and the numeral appearing in the adjacent notch or aperture 106, sets a row or pins in the row of holes corresponding to said numeral, when eventually the rotation of the 65 drum brings this set of pins into position to

actuate the punches, the same numeral designating that particular set of pins will appear at the notch 109 adjacent the word "Punch."

The general operation of the specific embodiment hereinbefore described is as follows:—The operator draws the free end of the sheet 16 from the roll 15 beneath the tension-bar 28 beneath the guide-plate 72 and guide 102 to a point adjacent the top 75 of the feed rolls. In case the machine is to perforate in the sheet the holes for the feeding of the latter, it will be necessary to attach to the free end of the sheet a small piece of previously perforated sheet and 80 place the perforations upon the teeth of the feed-wheels, so that the initial feeding of the sheet can be begun. The operator then, with the aid of the designer's draft, beginning at the top of the latter with the symbols on the line A—A, places in the drum a longitudinal series of pins corresponding to the symbols "R," "1" and "W." When eventually the rotation of the drum brings this set of pins into coöperation with the 85 corresponding wipers to actuate the corresponding punches, the sheet will be punched with a corresponding series of perforations along the line A—A (Fig. 9) of the sheet. At the same time, the two perforations 33 90 will be punched adjacent opposite edges respectively of the sheet for the feeding of the latter. The placing of the pins and the punching of the sheet now continues in an obvious manner, the operator referring to 100 the designer's draft and placing the pins in corresponding positions in the drum by the aid of the indexes, and after placing each set of pins, grasps the handle 50, giving the wheel 49 one complete rotation, thereby 105 causing one row of perforations to be made in the sheet and the latter subsequently fed along into position to receive the next row of perforations, and so on.

In order to avoid the use of an extremely 110 long pattern sheet, the width of the latter may be utilized to provide an entirely separate and distinct set of perforations placed between the perforations previously made, so that when in the operation of the warp 115 drawing machine the first set of perforation has completed its coöperative action with the mechanism controlled thereby, the pattern sheet may be shifted into position to bring the second set of perforations into position to coöperate with the mechanism of the warp drawing machine controlled thereby. For this purpose, the pattern sheet, after it has received one set of perforations as above described, may be shifted laterally 120 into a new predetermined position differing from the first position by one-half the distance between the rows of the first set of perforations. This may be accomplished by removing the guide 18 from the groove 20, 125 130

and setting the same into the groove 22, removing the guide 19 from the groove 21, and setting the same into the groove 23, and setting the feed-wheels 31 laterally a corresponding distance by shifting the shaft 34 as hereinbefore described by the aid of the pin 58 and grooves 56 and 57. It will readily be seen that with the sheet thus positioned with respect to the perforating devices, the sheet will be perforated with an independent set of perforations, the latter being indicated in dotted lines in Fig. 9 for the purpose of distinguishing them from the perforations of the first set, which are shown in full lines.

While I have herein shown and described one form of my invention for illustrative purposes, and have disclosed and discussed in detail the construction and arrangement incidental to one specific embodiment thereof, it is to be understood that the invention is limited neither to the mere details or relative arrangement of parts, nor to its specific application herein shown, but that extensive deviations from the illustrated form or embodiment of the invention may be made without departing from the principles thereof.

Having thus described one embodiment of my invention, what I claim is:

1. In a machine for perforating pattern sheets, the combination of means for feeding the sheet longitudinally; means comprising a series of members for perforating a longitudinal succession of transverse series of holes of a certain predetermined arrangement in the sheet; and means permitting the perforating means to be arranged and re-arranged at the will of the operator, whereby the number and arrangement of the holes of each transverse series may be selected at will.

2. In a machine for perforating pattern sheets, the combination of means for feeding the sheet longitudinally; means comprising a series of perforating members and actuators for perforating a longitudinal succession of transverse series of holes of a certain predetermined arrangement in the sheet; and means permitting said actuators to be arranged and rearranged in various transverse arrangements manually at the will of the operator, whereby the number and arrangement of the holes of each transverse series may be selected at will.

3. In a machine for perforating pattern sheets, the combination of means for perforating the sheet, means for feeding the sheet, and means for relatively positioning the perforating means and feeding means in a plurality of positions transversely of the sheet.

4. In a machine for perforating pattern sheets, the combination of means for perforating the sheet, means for feeding the

sheet, means for guiding the sheet, and means for relatively positioning the perforating means, guiding means, and feeding means in a plurality of positions transversely of the sheet.

5. In a machine for perforating pattern sheets, the combination of means for perforating the sheet, means for feeding the sheet, and means for relatively positioning the perforating means and feeding means in a plurality of predetermined positions transversely of the sheet.

6. In a machine for perforating pattern sheets, the combination of means for perforating the sheet, means for feeding the sheet, means for guiding the sheet, and means for relatively positioning the perforating means, guiding means, and feeding means in a plurality of predetermined positions transversely of the sheet.

7. In a machine for perforating pattern sheets, the combination of means for perforating the sheet in longitudinal rows, means for feeding the sheet, and means for relatively positioning the perforating means and feeding means in two predetermined positions transversely of the sheet, differing from each other by one-half the distance between the rows of perforations.

8. In a machine for perforating pattern sheets, the combination of means for perforating the sheets in longitudinal rows, means for feeding the sheet; means for guiding the sheet, and means for relatively positioning the guiding means and perforating means in two predetermined positions transversely of the sheet, differing from each other by one-half the distance between the rows of perforations.

9. In a machine for perforating pattern sheets, the combination of means for making perforations in the sheet including a continuous row of perforations, rotary sheet feeding means for feeding the sheet by engagement with the perforations of said row, and means for relatively positioning the perforating means and feeding means in a plurality of positions transversely of the sheet.

10. In a machine for perforating pattern sheets, the combination of means for perforating the sheet, means for feeding the sheet, a table across which the sheet is fed, and a pair of sheet edge guides, said table having provision to hold said guides in a plurality of predetermined positions transversely of the sheet.

11. In a machine for perforating pattern sheets, the combination of means for perforating the sheet, means for feeding the sheet, a table across which the sheet is fed, and a pair of sheet edge guides, said table being provided with two sets of longitudinal recesses to receive and hold said guides in position to guide the sheet.

12. In a machine for perforating pattern

- sheets, the combination of means for perforating the sheet, rotary sheet feeding means including a shaft, and means to position said shaft and feeding means in a plurality 5 of positions transversely of the sheet.
13. In a machine for perforating pattern sheets, the combination of means for perforating the sheet, rotary sheet feeding means including a shaft having means provided 10 with a plurality of circumferential grooves, and a positioning element to coöperate with one of said grooves.
14. In a machine for perforating pattern sheets, the combination of means for perforating the sheet, rotary sheet feeding means including a shaft having means provided 15 with a plurality of circumferential grooves, and a longitudinally slidable positioning pin normally entering one of said grooves.
15. In a machine for perforating pattern sheets, the combination of means for perforating the sheet, rotary sheet feeding means including a shaft having means provided 20 with a plurality of circumferential grooves, and a longitudinally slidable positioning pin normally entering one of said grooves and having a reduced portion normally out of 25 register with said shaft.
16. In a machine for perforating pattern sheets, the combination of means for feeding 30 the sheet; sheet perforating means including a punch; a rotary drum; a pin inserted radially in drum for actuating said punch; a movable wiper interposed between 35 said drum and said punch; and means to cause rotative movement of said drum and pin to act through said wiper to actuate said punch.
17. In a machine for perforating pattern sheets, the combination of means for feeding 40 the sheet, and sheet perforating means including a punch, a rotary drum, a pin loosely carried by said drum, and means normally to hold said pin in coöperative engagement with said drum.
18. In a machine for perforating pattern sheets, the combination of means for feeding the sheet, and sheet perforating means including a punch, a rotary drum provided 45 with a hole, a pin loosely mounted in said hole, and a guard normally to hold said pin in said hole.
19. In a machine for perforating pattern sheets, the combination of means for feeding 50 the sheet, and sheet perforating means including a punch, a rotary drum provided with a hole, a pin loosely mounted in said hole, and a casing encircling said drum normally to hold said pin in said hole.
20. In a machine for perforating pattern sheets, the combination of means for feeding 55 the sheet, and sheet perforating means including a punch, a rotary drum provided with a hole, a pin loosely mounted in said hole, and a casing encircling said drum normally to hold said pin in said hole.
- hole, and a casing encircling said drum normally to hold said pin in said hole, said casing being provided with an aperture permitting removal and replacement of said pin. 65
21. In a machine for perforating pattern sheets, the combination of a plurality of punches, a drum provided with a plurality of holes, a plurality of pins removably carried by said holes for actuating said punches, respectively, means normally holding said pins in their respective holes but permitting them to be manually removed and rearranged, and means for causing the rotative movement of said drum to actuate said punches. 70
22. In a machine for perforating pattern sheets, the combination of a plurality of punches, a drum provided with a plurality of circumferential series of holes, and a plurality of pins loosely carried in said holes for actuating said punches respectively. 80
23. In a machine for perforating pattern sheets, the combination of a plurality of punches, a drum provided with a plurality of circumferential series of holes, a plurality of pins carried in said holes for actuating said punches respectively, and a casing inclosing said drum and normally holding said pins in said holes. 85
24. In a machine for perforating pattern sheets, the combination of a plurality of punches, a drum provided with a plurality of circumferential series of holes, a plurality of pins carried in said holes for actuating said punches respectively, and a casing inclosing said drum and normally holding said pins in said holes, said casing being provided with an aperture in its upper side. 90
25. In a machine for perforating pattern sheets, the combination of a plurality of punches, a drum provided with a plurality of holes, a plurality of pins carried by said holes for actuating said punches respectively, and an indexing device for said pins. 100
26. In a machine for perforating pattern sheets, the combination of a plurality of punches, a drum provided with a plurality of circumferential series of holes, a plurality of pins carried in said holes for actuating said punches, respectively, and an indexing device associated with said drum 110 and pins.
27. In a machine for perforating pattern sheets, the combination of a plurality of punches, a drum provided with a plurality of circumferential series of holes, a plurality of pins carried in said holes for actuating said punches, respectively, and an indexing device having symbols associated 120 with said series of holes respectively.
28. In a machine for perforating pattern sheets, the combination of a plurality of punches, a drum provided with a plurality of longitudinal series of holes, a plurality 125

of pins carried in said holes for actuating said punches, respectively, and an indexing device for said longitudinal series of holes.

29. In a machine for perforating pattern sheets, the combination of a plurality of punches, a drum provided with a plurality of longitudinal series of holes, a plurality of pins carried in said holes for actuating said punches, respectively, and an index wheel carried by said drum.

30. In a machine for perforating pattern sheets, the combination of a plurality of punches, a drum provided with a plurality of longitudinal series of holes, a plurality of pins carried in said holes for actuating said punches, respectively, and a pair of index wheels carried by said drum and provided, respectively, with series of symbols.

31. In a machine for perforating pattern sheets, the combination of a plurality of punches, a drum provided with a plurality of longitudinal series of holes, a plurality of pins carried in said holes for actuating said punches, respectively, and a pair of index wheels carried by said drum and provided, respectively, with series of symbols, the symbols of one wheel corresponding in character to the symbols of the other but located in a different position circumferentially.

32. In a machine for punching pattern sheets, the combination of means for punching the sheet, means for holding a supply of sheet material, means for feeding the sheet from the supply to said punching means, sheet tensioning means interposed between said supply and said punching

means, said sheet tensioning means including a friction bar adapted to rest on the sheet, and sheet guiding means including a plurality of guides held in place by said friction bar.

33. In a machine for punching pattern sheets, the combination of means for punching the sheet, means for holding a supply of sheet material, means for feeding the sheet from the supply to said punching means, sheet tensioning means interposed between said supply and said punching means, said sheet tensioning means including a friction bar adapted to rest on the sheet, and sheet guiding means including a pair of guides provided with notches to receive said friction bar.

34. In a machine for punching pattern sheets, the combination of means for punching the sheet, means for holding a supply of sheet material, means for feeding the sheet from the supply to said punching means, sheet tensioning means interposed between said supply and said punching means, said sheet tensioning means including a friction bar adapted to rest on the sheet, and sheet guiding means including a pair of guides, the friction surface of said bar being intermediate the top and bottom of said guides.

In testimony whereof, I have signed my name to this specification, in the presence of two subscribing witnesses.

CHARLES LEA.
